FOLDABLE PACK FOR FRAGILE ARTICLES

Ernest L. Shepard, Fairfield, Maine, assignor, by
mesne assignments, to The Canal National
Bank of Portland, Portland, Maine, a national
banking association, and William B. Nulty,
Portland, Maine, as trustees

Application February 28, 1948, Serial No. 144,833

Term of patent 14 years

(Cl. D58—13)

To all whom it may concern:

Be it known that I, Ernest L. Shepard, a citizen of the United States, residing at Fairfield, in the county of Somerset, State of Maine, have invented a new, original, and ornamental Design for a Foldable Pack for Fragile Articles, of which the following is a specification, reference being had to the accompanying drawing, forming part thereof.

Fig. 1 is a top plan view of a foldable pack for fragile articles, showing my new design, the pack being open.

Fig. 2 is an end view of Fig. 1.

Fig. 3 is an end view of the pack when folded into closed position, and

Fig. 4 is a sectional view of the pack taken on line 4—4 of Fig. 1.

I claim:

The ornamental design for a foldable pack for fragile articles, as shown.

ERNEST L. SHEPARD.
